BAILER

Filed Dec. 12, 1927

INVENTOR

Colnd C. Heeter,
by his Atty.,
Bynes, Stilson Kennedy

UNITED STATES PATENT OFFICE

COLONEL C. HEETER, OF BUTLER, PENNSYLVANIA, ASSIGNOR TO C. M. HEETER SONS & COMPANY, INC., OF BUTLER, PENNSYLVANIA, A CORPORATION OF PENNSYLVANIA

BAILER

Application filed December 12, 1927. Serial No. 239,339.

The present invention relates broadly to the art of drilling, and more particularly to tools of the character ordinarily referred to as dart valve bailers.

It is customary in the art to which the present invention relates to periodically suspend drilling operations and effect the removal of accumulated free material within the hole by the use of pumps, bailers, or the like, of a wide variety of different types. With all such equipment, the speed with which the accumulated material may be removed from an opening is of importance, as is also the strength and durability of the equipment itself. In accordance with the present invention, there is provided an improved bailer of the type commonly referred to as a dart valve bailer, and so constructed as to provide a valve chamber of maximum diameter and to provide operative connections between the various parts, such that the length of life is considerably increased, and improved results obtained.

The accompanying drawing illustrates more or less diagrammatically in longitudinal section, partly broken away, and partly in elevation, one form of bailer constructed in accordance with the present invention, it being understood that the drawings do not define the limits of my invention as changes in the construction disclosed therein may be made without departing either from the spirit of the invention or the scope of my broader claims.

In carrying out the present invention, there may be provided an upper sleeve 2, provided with an upper bail 3, which may be formed integrally therewith or swedged, or otherwise secured thereto in accordance with present practice.

The sleeve 2 is also formed with a downwardly projecting bail 4 of a construction preferably generally similar to the construction of the bail 3, although changes therein may be made as desired.

The lower portion of the bailer is formed by a sleeve 5 having its lower end enlarged to form a valve body 6. The upper end of the sleeve 5 is provided with a bail 7, similar to the bail 4, these bails being adapted to be

connected in accordance with the present invention, by a cable, wire, or the like, 8, whereby the load of the parts is directly carried by this connecting means. Each of the sleeves 2 and 5 is conveniently formed with a threaded outer surface 9, terminating in a shoulder 10, the threads and shoulders being adapted for cooperation with a flexible tube or hose 11. This flexible tube may be secured in position about the threaded portions by 55 binding wires, or the like, 12, such binding wires preferably being tight enough to cause the tube to undergo a change of section as it passes over the shoulders 10 whereby part of the weight of the tube is carried by the shoulders, the binding wires being relieved to a 60 corresponding extent.

At its lower portion beginning at its substantially mid-section, the tube or hose 11 is preferably thickened, as clearly indicated in 70 the drawings, whereby distortion thereof under the weight of material contained within the bailer is minimized, bulging being substantially prevented. This is particularly 75 desirable where a load carrying member 8 is employed for carrying the actual weight of the parts, since such a member reduces the tendency of the flexible tube or hose to elongate, and leaves it free to yield laterally.

The valve chamber 6 may carry a valve 80 seat 13, with which cooperates a dart valve 14 of any well known construction. It will be apparent from the drawings that the internal diameter of the valve chamber 6 is substantially equal to the diameter of the 85 tube 11 thereby providing a maximum capacity, and permitting the use of openings and valve parts of such dimensions that a maximum flow of accumulated material from the well to the interior of the bailer is permitted.

Certain advantages of the present invention arise from the provision of a bailer comprising upper and lower members, connected by a flexible tube in combination with means 95 for relieving from the tube the actual weight of the parts.

Other advantages of the invention arise from the provision of employing in the bailer a flexible tube of an increased thick- 100

ness in the lower section, minimizing bulging thereof.

Still other advantages arise from the use of a bailer having a valve body of maximum 5 diameter whereby the capacity of the bailer is increased.

I claim:—

1. In a bailer, an upper member having a bail formed on the lower end thereof, a lower 10 member having a bail formed on the upper end thereof, an elongated tubular member of rubber extending between said upper and lower members, and load carrying means directly connecting said bails.
15. 2. In a bailer, an upper member having a bail formed on the lower end thereof, a lower member having a bail formed on the upper end thereof, an elongated tubular member of rubber extending between said upper and 20 lower members, and load carrying means directly connecting said bails and positioned entirely within said tubular member.
25. 3. In a bailer, a flexible tubular casing of rubber, a sleeve within the lower end of said casing for maintaining the casing extended, a valve chamber carried by said sleeve, and having an outside diameter substantially equal to the diameter of said casing, and a valve operative within said chamber.
30. 4. In a bailer, an upper member having a bail formed on the lower end thereof, a lower member having a bail formed on the upper end thereof, an elongated tubular member of flexible material extending between 35 said upper and lower members, load carrying means directly connecting said bails and positioned entirely within said tubular member for relieving from said casing the weight of material lifted by the bail, and a valve 40 carried by said lower member.
45. 5. In a bailer, an upper member having a bail formed on the lower end thereof, a lower member having a bail formed on the upper end thereof, an elongated tubular member of flexible material extending between said upper and lower members, said tubular member having a wall, the thickness of which is greater below substantially the middle thereof, load carrying means directly connecting 50 said bails and positioned entirely within said tubular member, and a valve carried by said lower member.

In testimony whereof I have hereunto set my hand.

COLONEL C. HEETER.
